FURNITURE STRUCTURE

Max Koenigsberg, Highland Park, Ill., assignor to The Englander Company, Inc., Chicago, Ill., a corporation of Delaware

Application October 5, 1954, Serial No. 460,472

9 Claims. (Cl. 155—180)

The present invention relates to a novel furniture structure and more particularly, to a furniture structure including a metal frame, a spring unit, and covering fabric secured together in the novel manner and adapted to be used in furniture such as chairs, divans, beds, vehicle seats, and the like.

An important object of the present invention is to provide a novel furniture structure wherein a spring unit and a covering fabric are secured to a metal frame member in a simple and economical manner.

Another object of the present invention is to provide a novel furniture structure wherein a spring unit and covering fabric are secured to a metal frame member without the aid of auxiliary fastening devices such as screws, staples and the like.

A more specific object of the present invention is to provide a novel furniture structure of the above described type wherein the metal frame member includes integral means for securing a spring unit and covering fabric thereto.

Other objects and advantages of the present invention will become apparent from the following description and the accompanying drawings wherein:

Fig. 1 is a fragmentary cross sectional view showing a piece of furniture embodying the novel structure of this invention;

Fig. 2 is an enlarged fragmentary perspective view showing the novel structure of this invention in a partially assembled condition;

Fig. 3 is a fragmentary cross sectional view showing the novel structure of this invention in its fully assembled condition;

Figs. 4 and 5 are cross sectional views of a slightly modified form of the present invention and respectively showing the structure in a partially assembled and fully assembled condition;

Fig. 6 is a fragmentary plan view of the novel structure of this invention;

Fig. 7 is a fragmentary perspective view showing another modified form of the present invention in a partially assembled condition;

Fig. 8 is a fragmentary perspective view of the structure shown in Fig. 7 in its fully assembled condition;

Fig. 9 is a fragmentary cross sectional view showing a further modified form of the present invention which incorporates certain features of the structures shown in Figs. 3 and 8;

Fig. 10 is a fragmentary cross sectional view of another modified form of the present invention which incorporates other features of the structures shown in Figs. 3 and 8;

Figs. 11 and 12 are fragmentary cross sectional views respectively showing still another modified form of the present invention in a partially assembled and fully assembled condition; and

Fig. 13 is a fragmentary plan view of the structures shown in Figs. 7 and 8.

2

Referring now more specifically to the drawings wherein like parts are designated by the same numerals throughout the various figures, a piece of furniture 20 incorporating the principles of the present invention is partially shown in Figs. 1 and 6 and includes a generally rectangular frame 22 provided by sheet metal frame members 24, a plurality of frame supporting legs 26, only one of which is shown, a spring unit 28, a fabric dust cover 30 disposed on the frame and beneath the spring unit, an outer covering fabric 32 and a cushion or mattress 34. The spring unit may be of any desired structure which includes a plurality of coil springs 36.

As shown best in Figs. 2 and 3, each of the sheet metal frame members 24 includes a vertical web portion 38 having horizontal flanges 40 and 42, respectively, extending inwardly of the frame from upper and lower margins of the web portion. Preferably, the web portion is formed with a centrally located longitudinally extending channel section 43 for increasing the strength and rigidity thereof.

In accordance with the present invention, the spring unit and the fabric panels 30 and 32 are secured in assembled relationship with the metal frame member in an extremely simple and therefore economical manner. More specifically, the spring unit is secured to the metal frame member by striking a plurality of tabs 44 from the upper flange 40 of the frame member, which tabs are arranged in alignment with the individual coil springs of the unit as shown in Fig. 6. The tabs 44 are initially formed so that they extend upwardly as shown in Fig. 2 and after the spring unit has been placed on the metal frame, each of the tabs is bent around a portion of the bottom end wire coil 47 of an associated coil spring as shown in Fig. 3.

In order to simplify the structure, the cover 30 is also secured to the frame members by means of the tabs 44. Thus, before the spring unit is placed on the frame members, the dust cover 30 is stretched across the frame members and impaled on the pointed tabs 44. Upon subsequent assembly of the spring unit and folding of the tabs 44 in the manner described above, the dust cover will be permanently and securely fastened in position.

In the embodiment shown in Figs. 2 and 3, the outer covering fabric panel 32 is secured to the metal frame members by means of a plurality of pointed tabs 48 struck from the lower flanges 42 of the frame members. As shown in Fig. 2, the tabs 48 are initially formed so that they extend downwardly from the frame member whereby a marginal edge of the fabric panel 32 may be easily impaled thereon. After the marginal edge 32 has been placed onto the tabs, the tabs 48 are preferably bent rearwardly and toward the flange 42, as shown in Fig. 3, to fasten the panel in a secure manner. In order substantially to eliminate any possibility of the fabric 32 being torn or otherwise injured by the tabs 48, the margin of the panel is folded and sewn to provide a double thickness hem and an elongated wire 50 is inserted through the hem. This wire serves to spread any undue stresses applied to the fabric at the tabs 48 so as to prevent tearing of the fabric.

Figs. 4 and 5 show a slightly modified form of the present invention which is substantially identical to the above structure as indicated by the application of identical reference numerals with the suffix "a" added to corresponding elements. This embodiment differs only in that the tabs 44a and 48a are formed so that they are positioned reversely of the similar tabs 44 and 48 described above. With this arrangement the folding of the tabs 44a to their final positions is facilitated since they may be folded by means of a blunt instrument, not shown, pressed inwardly against the covering panel 32a. In addition, this arrangement of the tabs 48a provides

a more secure fastening of the margin of the panel 32a since the tabs may be folded so that the hem and wire are tightly clamped against the flange 42a.

In Figs. 7, 8 and 13, there is shown another modified form of the present invention which is similar to the above described structures as indicated by the application of identical reference numerals with the suffix "b" added to corresponding elements. In this embodiment, an elongated fabric strip 52 is sewn to the panel 32b as at 54 and 56 to provide a loop positioned to overlie the upper flange 40b of the frame member. An elongated wire 50b is inserted within the double thickness flap provided by the fabric strip. With this additional structure, the fabric panel 32b is primarily secured to the frame member by inserting the tabs 44b through the fabric strip as shown in Fig. 7 and wrapping the tabs around the wire 50b as shown in Fig. 8. Preferably, the fabric panel 32b is extended downwardly as indicated by the reference numeral 58 to cover the outer surface of the frame member and this portion of the panel may be glued to the frame member so that it will present a pleasant, smooth appearance.

In the structure shown in Figs. 7, 8 and 13, the spring unit is provided with a border wire 60 of known construction and secured to the coil springs in any known manner such as by staples 62. In addition, the tabs 44b are arranged between the coil springs rather than in alignment therewith. Thus, in order to secure a spring unit to the frame member, the tabs 44b are wrapped around portions of the border wire 60.

In certain instances, it may be desirable to arrange the dust cover beneath the metal frame rather than on top of the metal frame. This arrangement of the dust cover is shown in Figs. 7 and 8 and the dust cover is secured to the frame by means of the tabs 48b.

Fig. 9 shows a modified form of the present invention which incorporates certain features of the structures illustrated in Figs. 3 and 8 as indicated by the application of identical reference numerals with the suffix "c" added to corresponding elements. It is seen that in the structure shown in Fig. 9, the fabric panel 32c is provided with a double thickness flap 52c through which a wire 50c extends so that the panel may be secured to the frame member by means of the tabs 44c. More specifically, the structure is similar to that shown in Fig. 3 in that the dust cover 30c is first arranged across the top of the frame member and impaled on the tabs, and the tabs are disposed in alignment with the coil springs of the frame unit and are wrapped around end coils of the springs.

Fig. 10 discloses another slightly modified form of the present invention which is most similar to the embodiment shown in Fig. 8 as indicated by the application of identical reference numerals with the suffix "d" added to corresponding elements. This embodiment differs in that the dust cover 30d is arranged on top of the frame members and is secured by the tabs 44c in the same manner that it is secured in the structure shown in Fig. 3 described above. With this structure as well as the structure shown in Fig. 9, it is seen that the same tabs may be used for securing both of the fabric panels and the spring unit in assembled relationship with the frame members.

Figs. 11 and 12 illustrate still another slightly modified form of the present invention as indicated by the application of identical reference numerals with the suffix "e" added to corresponding elements. In this embodiment, the outer cover panel 32e is formed so that it terminates at the upper edge of the frame member 24 whereby considerable savings in material may be effected. The prongs or tabs 44e are inserted through the hem of the panel 32e and wrapped around the wire 50e as shown in Fig. 12. In addition, the prongs 44e are wrapped around the border wire 60e for securing the spring unit

to the frame member. While the prongs 44e are shown as being wrapped around the border wire, it was understood that the prongs or tabs may be arranged in alignment with the coil springs of the spring unit and wrapped around end coils of the springs in the manner described above. It should be noted that in this embodiment, the tabs 44e are struck from the flange 40e so that they extend upwardly from the vertical web 38e of the frame member. With this arrangement, the hem of the fabric panel 32e is fixed so that the panel is in vertical alignment with the web 38e so as to provide a pleasing appearance. If the tabs 44e were located inwardly of the web as are the similar tabs described above, the fabric panel 32e would be pulled inwardly over the top of the frame member.

From the above description, it is seen that the present invention has provided a simple and economical structure for use in various pieces of furniture such as chairs, divans, beds, vehicle seats and the like. More specifically, it is seen that the present invention has provided a novel structure wherein a spring unit and one or more fabric panels may be easily and economically secured in assembled relationship with a metal frame member by means of tabs integral with the frame member.

While the preferred embodiments of the present invention have been shown and described above, it is obvious that many structural details may be changed without departing from the spirit and scope of the appended claims.

The invention is claimed as follows:

1. A furniture structure of the type described comprising a rectangular support frame including sheet metal side frame members having generally horizontal flanges, a spring unit disposed on said frame member flanges, a fabric panel associated with said frame members, and integral tab means struck from said frame member flanges, impinging said fabric panel and formed around wire portions of said spring unit for securing said frame members, said spring unit and said fabric panel in assembled relationship.

2. A furniture structure of the type described comprising a rectangular support frame including sheet metal side frame members having generally horizontal flanges, a spring unit disposed on said frame member flanges, a fabric panel associated with said frame members, and a plurality of integral tab means struck from within boundaries of said frame member flanges, each of said tab means impinging said fabric panel and also confining a wire portion of said spring unit for securing the frame members, the spring unit and said fabric panel in assembled relationship.

3. A furniture structure of the type described comprising a rectangular support frame including sheet metal side frame members having upper inturned generally horizontal flanges, a spring unit disposed on said frame member flanges, a fabric means associated with said frame members, and a plurality of integral tabs struck from said frame member flanges, each of said tabs impinging said fabric means and confining an end coil of a coil spring in the spring unit for securing said frame members, said spring unit and said fabric means in assembled relationship.

4. A furniture structure of the type described comprising a rectangular support frame including sheet metal side frame members having upper inturned generally horizontal flanges, a spring unit disposed on said frame member flanges, fabric means associated with said frame members, and a plurality of integral tabs struck from said frame member flanges, each of said tabs impinging said fabric means and confining a portion of a border wire of said spring unit for securing said frame members, said spring unit and said fabric means in assembled relationship.

5. A furniture structure of the type described comprising a rectangular support frame including sheet metal

side frame members having generally horizontal flanges, a dust cover disposed on said frame member flanges, a spring unit disposed on said frame member flanges and over said dust cover, and integral tab means struck from said frame member flanges, said tab means impinging said dust cover and encircling a wire portion of said spring unit for securing said frame members, said spring unit and said dust cover in assembled relationship.

6. A furniture structure of the type described comprising a rectangular support frame including sheet metal side frame members having generally horizontal flanges, a spring unit disposed on said frame member flanges, fabric panel means covering said spring unit, and a plurality of integral tabs struck from said frame member flanges, said fabric panel means having a folded portion impinged by said tabs and an elongated wire extending longitudinally through said folded portion, said tabs being formed around said elongated wire and around a wire portion of said spring unit for securing said frame members, said spring unit and said fabric means in assembled relationship.

7. A furniture structure of the type described comprising a rectangular support frame including sheet metal side frame members having upper inturned generally horizontal flanges, a dust cover disposed on said frame member flanges, a spring unit disposed on said frame member flanges and over said dust cover, fabric panel means covering said spring unit, and a plurality of integral tab means struck from said frame member flanges, each of said tab means impinging said dust cover and said fabric panel means, and confining a portion of said spring unit for securing said frame members, said spring unit, said dust cover and said fabric panel means in assembled relationship.

8. A furniture structure of the type described com- 35

prising a rectangular support frame including sheet metal side frame members each having a substantially vertical web and a substantially horizontal flange extending inwardly from an upper margin of said web, a spring unit disposed on said flanges, a fabric panel covering said spring unit and depending along said web, flap means secured to said fabric panel and extending over said flanges, and integral tab means struck from said flanges, said tab means impinging said flap means and confining a portion of said spring unit for securing said frame members, said spring unit and said fabric panel in assembled relationship.

9. A furniture structure of the type described comprising a rectangular support frame including sheet metal side frame members each having a substantially vertical web portion and a generally horizontal flange extending inwardly from an upper margin of said web portion, a spring unit disposed on said flanges, a fabric panel covering said spring unit and having a bottom margin terminating at and in substantial vertical alignment with said upper margins of said frame member web portions, and integral tab means struck from said flanges and extending from said upper margins of said web portions, said tab means impinging said bottom margin, of said fabric panel, and confining a portion of said spring unit for securing said frame members, said spring unit and said fabric panel in assembled relationship.
